CLAIM

The ornamental design for a handheld engraver, substantially as shown and described.

DESCRIPTION

FIG. 1 is a top, right, front isometric view of a handheld engraver showing my new design;

FIG. 2 is a rear, left, bottom isometric view thereof;

FIG. 3 is a front side elevation view thereof;

FIG. 4 is a rear side elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines shown in the drawings depict portions of the handheld engraver that form no part of the claimed invention.
